UNITED STATES PATENT OFFICE.

THOMAS MOORE, OF SOUTH STOCKTON - ON - TEES, AND CHARLES A. HEAD,
OF STOCKTON - ON - TEES, ASSIGNORS TO HEAD, WRIGHTSON & CO., OF
THE TEESDALE IRON WORKS, STOCKTON - ON - TEES, COUNTY OF YORK,
ENGLAND.

PULLEY-BLOCK.

SPECIFICATION forming part of Letters Patent No. 249,443, dated November 8, 1881.

Application filed February 10, 1881. (No model.) Patented in England September 28, 1870.

To all whom it may concern:

Be it known that we, THOMAS MOORE, of South Stockton-on-Tees, in the county of York, England, engineer, and CHARLES ARTHUR HEAD, of the Teesdale Iron Works, Stockton-on-Tees, England, engineer, have invented new and useful Improvements in Pulley-Blocks for Raising and Lowering Sacks and other Weights, which improvements are fully set forth in the following specification, reference being had to the accompanying drawings.

This invention has for its object improvements in pulley-blocks for raising and lowering sacks and other weights. For this purpose we construct a pulley-block with a small chain-wheel, over which is passed a chain, to either end of which the sack or weight to be raised or lowered is attached. The small chain-wheel has cast concentric with it at one of its sides an internal toothed wheel, into which gears a pinion, cast at the side of and concentric with a driving-wheel, over the periphery of which an endless driving chain or cord is passed. The driving-wheel is of considerably larger diameter than the chain-wheel, and when the driving-wheel is turned, by pulling round the endless driving chain or cord a revolving motion is imparted at a reduced speed to the chain-wheel and to the lifting-chain which passes over it. The pins or axes upon which the chain-wheel and the driving-wheel revolve are formed in one piece, they being connected one with the other by a central crank-piece. The outer ends of the pins or axes are passed through the side bars of the pulley-frame, and are secured by nuts. The pulley-frame, as is usual, is provided with a hook, by which it can be suspended where desired.

In order that our said invention may be most fully understood and readily carried into effect, we will proceed to describe the drawings, hereunto annexed.

In the drawings, Figure 1 is a side view of a pulley-block constructed according to our invention. Fig. 2 is a cross-section of the

same; and Fig. 3 is a section taken at the line A B, Fig. 2.

a a is the frame of the pulley-block. It is provided with a hook, a', by which it may be suspended from any suitable support. b b is 50 a cranked axis or pin fixed in this frame. c is the chain-wheel, over which the lifting and lowering chain d is passed. It turns freely on the fixed axis or pin b. e is a ring of internal teeth cast in one piece with the chain-wheel c. f is 55 a pinion gearing with the ring of internal teeth e. The pinion f also turns freely on the axis or pin b, and the driving-wheel g is formed in one piece with it. An endless band, cord, or chain for actuating the apparatus is passed over 60 this wheel.

We are aware that pulley-blocks have heretofore been constructed in which two wheels or pulleys are employed, one working loose upon an eccentric and the other keyed to a straight 65 revolving shaft passing through and fixed to said eccentric, an oscillating plate and a cogged wheel gearing with internal teeth formed upon one pulley being arranged between said pulleys; but this is essentially different from ours both 70 in construction and operation, as it operates upon the principle of gaining one tooth or notch for each revolution of the driving-wheel, and as it is designed for lifting heavy weights the movement of the chain-wheel is very slow, as 75 each revolution requires as many complete turns of the driving-wheel as there are teeth on the eccentrically-operated pinion or inside wheel, while our device, which is designed for lighter weights and faster movements, has no 80 eccentrics or eccentric movements, as its operation is not essentially different from what it would be if the teeth e were on the outside and the pinion f exterior. By making it in the form shown we avoid separate framing and 85 bearings for the pinion, and reduce the whole to a simple, compact, and strong device, and cause the chain or lifting wheel to move faster than heretofore, and by the bend in the middle of the shaft b each exterior support oper- 90

ates as an interior support for each of the two axes, which has not heretofore been accomplished when the axes were not in line.

Having thus described the nature of our invention and the manner of performing the same, we would have it understood that we claim as our improvements in pulley-blocks for raising and lowering sacks and other weights—

The fixed bent shaft *b b* and frame *a*, in combination with the driving-wheel *g*, having the

pinion *f*, and lifting-wheel *c*, having the interior gear or cogs *e*, constructed and operating substantially as shown and described.

THOMAS MOORE.

CHARLES ARTHUR HEAD.
